CLAIM

The ornamental design for a controller with removable directional pad, as shown and described.

DESCRIPTION

FIG. 1 is a front perspective view of a controller with removable directional pad showing our new design in a first, attached state;

FIG. 2 is a top view thereof;

FIG. 3 is a front view thereof;

FIG. 4 is a rear view thereof;

FIG. 5 is a left side view thereof;

FIG. 6 is a right side view thereof;

FIG. 7 is a front perspective view of the controller with removable directional pad of FIGS. 1-6 shown in a second, removed state;

FIG. 8 is a top view thereof;

FIG. 9 is a front view thereof;

FIG. 10 is a rear view thereof;

FIG. 11 is a left side view thereof;

FIG. 12 is a right side view thereof; and,

FIG. 13 is a bottom view thereof.

The broken line showing of the various unshaded elements of the controller with removable directional pad in FIGS. 1-13 is for environmental purposes only and forms no part of the claimed design.
